UNITED STATES PATENT OFFICE

164,847

SHOE

Jean Dronoff, Watertown, Conn.

Application July 30, 1951, Serial No. 16,084

Term of patent 7 years

(Cl. D7—7)

To all whom it may concern:

Be it known that I, Jean Dronoff, a citizen of the United States of America, residing in Watertown, county of Richfield, and State of Connecticut, have invented a new, original, and ornamental Design for a Shoe, of which the following is a specification, reference being had to the accompanying drawing, forming part thereof.

The figure shown on the drawing is a perspective view of a shoe showing my new design.

The opposite side of the shoe is substantially the same as that shown, and the dominant feature of my design resides in the portion shown in solid lines.

I claim:

The ornamental design for a shoe, substantially as shown and described.

JEAN DRONOFF.
